(57) **CLAIM**

The ornamental design for a bilge pump housing, as shown and described.

DESCRIPTION

FIG. 1 is a top perspective view of a new design for a bilge pump housing.

FIG. 2 is a top view of the bilge pump housing of FIG. 1. FIG. 3 is a bottom view of the bilge pump housing of FIG. 1.

FIG. 4 is a front view of the bilge pump housing of FIG. 1. FIG. 5 is a rear view of the bilge pump housing of FIG. 1. FIG. 6 is a right side view of the bilge pump housing of FIG. 1; and,

FIG. 7 is a left side view of the bilge pump housing of FIG. 1.

In FIG. 3, the broken lines depict portions of the bilge pump housing that form no part of the claimed design.

1 Claim, 5 Drawing Sheets
